CLAIM

The ornamental design for a cargo-securement logistics track as shown and described.

DESCRIPTION

FIG. 1 is a front, right, upper perspective view of a cargo-securement logistics track showing the new design;

FIG. 2 is a front, left, lower perspective view thereof;

FIG. 3 is a back, right, upper perspective view thereof;

FIG. 4 is a back, left, lower perspective view thereof; and,

FIG. 5 is a front elevation view thereof.

The long-short dash lines depict boundaries of the design and do not form any part of the claimed design. The even dash lines depict portions of the cargo-securement logistics track forming no part of the claimed design.
